Primary Examiner — Kelley Donnelly(74) *Attorney, Agent, or Firm* — Steven R. Vosen(57) **CLAIM**

I claim the ornamental design for a triple end cap, as shown and described.

DESCRIPTION

FIG. 1 is an upper right front perspective view of a first embodiment of a triple end cap of the present invention; FIG. 2 is an enlarged perspective view of the triple end cap of FIG. 1; FIG. 3 is a front elevational view of the triple end cap of FIG. 1; FIG. 4 is a rear elevational view of the triple end cap of FIG. 1; FIG. 5 is a left elevational view of the triple end cap of FIG. 1, the right elevational view being the mirror image; and, FIG. 6 is a top plan view of the triple end cap of FIG. 1. The broken line showing of the display end cap is for the purpose of illustrating environmental structure, and forms no part of the claimed design.
